UNITED STATES PATENT OFFICE.

CHRISTIAN STEENSTRUP, OF SCHENECTADY, NEW YORK, ASSIGNOR TO GENERAL ELECTRIC COMPANY, A CORPORATION OF NEW YORK.

ELASTIC-FLUID TURBINE.

Application filed April 27, 1920, Serial No. 377,102. Renewed July 20, 1923.

To all whom it may concern:

Be it known that I, CHRISTIAN STEENSTRUP, a citizen of the United States, residing at Schenectady, county of Schenectady, State of New York, have invented certain new and useful Improvements in Elastic-Fluid Turbines, of which the following is a specification.

The present invention relates to elastic fluid turbines and has for its object to provide an improved structure and arrangement for fastening the bucket or vane ring or rings on the bucket-carrying member or wheel.

For a consideration of what I believe to be novel and my invention, attention is directed to the following description and the claims appended thereto.

In the drawing, Fig. 1 is a perspective view of a part of a turbine wheel embodying my invention; and Fig. 2 is a sectional view thereof.

Referring to the drawing, 5 indicates the web, 6 the rim, and 7 the buckets of a turbine wheel or rotor. The rim 6 is provided with a flat peripheral surface 8 and projecting centrally therefrom and running entirely around the wheel is an annular rib 9 provided with radially projecting circumferentially spaced spacing blocks 10. Buckets 7 fit between spacing blocks 10 and have notches 11 in one end in which rib 9 is located, the ends of the buckets resting against surface 8. The faces of blocks 10 are curved to conform to the contour of buckets 7 and are of a radial length to give a firm support for the buckets. On the outer ends of the buckets are tenons 12 by means of which a bucket cover 13 is fastened into place. The buckets are permanently and rigidly fixed to the wheel rim by fusion of metal, as by welding, brazing or the like and any suitable method may be used for this, although I prefer to fasten the buckets to the wheel rim by the method disclosed and claimed in my application, Serial No. 354,014, filed January 26, 1920. This method comprises placing the assembled structure in a suitable muffler containing a reducing atmosphere such as hydrogen and heating it, an alloying metal such as copper having been previously placed adjacent to the joints between the parts to be united. When heated to a suitable temperature, the copper enters the interstices between the parts and

unites them to each other to form in substance an integral structure. However, my invention is not necessarily limited to this specific method of uniting the parts and it is to be understood that by the term "fusion of metal", I mean the particular method referred to or other suitable method. If desired, the bucket cover may be fastened in a similar manner also.

In building up a turbine rotor embodying my invention, I first provide a wheel with a rim 6, rib 9 and spacing blocks 10, as shown. Spacing blocks 10 may be formed by cutting transverse slots in the outer portion of rib 9, while the rib itself may be formed by turning down the outer portion of rim 6. These are simple machine operations which can be easily and accurately performed. I then take buckets 7, as best shown at the left hand side of Fig. 1, and arrange them around the wheel, inserting a bucket between each two spacing blocks 10. As is clear, buckets 7 are formed from plain bucket stock, such as strips of extruded metal, or they may be drop forged, and they require no specially shaped or finished bases. All that is required is that they be provided with the notches 11 and tenons 12. After the buckets are assembled on the wheel, spacing blocks 10 are expanded circumferentially by calking them on the top so as to force them into firm engagement with the buckets and they may bite into the buckets, as shown in Fig. 2, in which figure the blocks 10 are shown as having been calked into engagement with the buckets. At the same time the buckets are driven in radially so their bottoms are in firm engagement with surface 8. After the buckets are thus assembled on the wheel, the bucket cover may be put into place and the buckets, wheel, and cover all united by fusion of metal as already referred to. When thus fastened, the buckets are firmly held both laterally and circumferentially and are accurately positioned and spaced.

With my improved arrangement, the buckets may be quickly assembled on the wheel by relatively unskilled help and it is to be noted that no filling slots are required and that there are no inside surfaces to be finished and carefully dimensioned.

In accordance with the provisions of the patent statutes, I have described the principle of operation of my invention together

with the apparatus which I now consider to represent the best embodiment thereof, but I desire to have it understood that the apparatus shown is only illustrative and that the invention may be carried out by other means.

What I claim as new and desire to secure by Letters Patent of the United States is:—

1. In an elastic fluid turbine, the combination 10 of a bucket carrying member having a flat peripheral surface, an annular rib extending around said surface and provided with spacing blocks, and buckets located between said blocks, said buckets having notches which receive the rib.
2. In combination, a bucket-carrying member having a rim provided with a flat peripheral surface and spacing blocks projecting therefrom, and buckets having their 20 inner ends located between said blocks and in engagement with said flat surface.
3. In combination, a bucket-carrying member having a rim provided with a flat peripheral surface and spacing blocks projecting therefrom, and buckets having their 25 inner ends located between said blocks and in engagement with said flat surface, said buckets being fastened to said flat surface and blocks by fusion of metal.
- 30 4. In combination, a bucket-carrying member having a rim provided with a flat peripheral surface and an annular rib projecting therefrom, and buckets having ends

in engagement with said flat surface and notches in which said rib fits, said buckets being fastened to said rim and rib by fusion of metal.

5. In combination, a bucket-carrying member having a rim provided with a flat peripheral surface and an annular rib projecting therefrom, and buckets having ends 40 in engagement with said flat surface and notches in which said rib fits, said rim being slotted to receive the buckets to space them circumferentially.

6. In combination, a bucket-carrying member having a rim provided with a flat peripheral surface and an annular rib projecting therefrom, and buckets having ends 45 in engagement with said flat surface and notches in which said rib fits, said rim being slotted to receive the buckets to space them circumferentially, said buckets, rim and rib being fastened together by fusion of metal.

7. In combination, a bucket-carrying member having a rim provided with a flat peripheral surface and an annular rib having straight sides, and buckets having ends 50 in engagement with said flat surface and notches the sides of which engage the straight sides of said rib, said buckets being fastened to said rib and rim by fusion of metal.

In witness whereof I have hereunto set my hand this 26th day of April, 1920.

CHRISTIAN STEENSTRUP.
